UNITED STATES PATENT OFFICE

165,778

SPILLPROOF GLASS

Edward F. Olsen, Hillman, Mich.

Application November 17, 1950, Serial No. 13,029

Term of patent 14 years

(Cl. D36—8)

To all whom it may concern:

Be it known that I, Edward F. Olsen, a citizen of the United States, residing at Hillman, in the county of Montmorency, and State of Michigan, have invented a new, original, and ornamental Design for a Spillproof Glass, for which the following is a specification, reference being had to the accompanying drawing, forming part thereof, in which:

Fig. 1 is a front elevational view of a spillproof glass showing my new design.

Fig. 2 is a side elevational view.

Fig. 3 is a top plan view; and

Fig. 4 is an exploded fragmentary side elevational view thereof.

The container is symmetrical about its vertical axis, and the bottom of the container is a flat surface slightly elevated from the lower outer peripheral edge of said container.

The dominant features of the design reside in the container cover of circular form having a beaded annular base, rounded upper corners and a flattened, perforated, upright spout situated at a side of the flat top as shown.

I claim:

The ornamental design for a spillproof glass, substantially as shown and described.

EDWARD F. OLSEN.
